UNITED STATES PATENT OFFICE.

ROBERT HIRSCH, OF MILWAUKEE, WISCONSIN, ASSIGNOR OF ONE-HALF TO
HERMAN MEMINGER, OF SAME PLACE.

COMMUTATOR-BRUSH.

SPECIFICATION forming part of Letters Patent No. 471,792, dated March 29, 1892.

Application filed October 29, 1891. Serial No. 410,165. (No model.)

To all whom it may concern:

Be it known that I, ROBERT HIRSCH, a citizen of the United States, and a resident of Milwaukee, in the county of Milwaukee, and 5 in the State of Wisconsin, have invented certain new and useful Improvements in Commutator-Brushes; and I do hereby declare that the following is a full, clear, and exact description thereof.

10 My invention relates to certain new and useful improvements in commutator-brushes for electric motors and dynamo-electric machines; and it consists in the matters herein-after described, and pointed out in the app- 15 pended claims.

In the accompanying drawings, illustrating my invention, Figure 1 is a perspective view of a strip or bar of graphite coated with a film of copper and adapted for use as a commutator-brush. Fig. 2 is a similar view of a commutator-brush composed of a number of such strips or bars united together.

In said drawings, A represents the strip of graphite; B, the film of copper, applied in any 25 suitable manner—as, for instance, by the electro-deposition of the metal upon the surface of the graphite. These strips or bars of graphite may be made of any desired or convenient shape and size, and for use upon small-sized 30 machines may be used singly. The brushes for use upon large-sized machines may be composed of a single block or piece of graphite, or may be composed of a plurality of smaller strips or bars placed side by side and 35 clamped together or otherwise united, as by a second film of electrically-deposited metal.

Brushes made in accordance with my invention may be used in precisely the same manner as the ordinary forms of brushes, and 40 may be clamped or otherwise secured in the usual brush-holders.

By the employment of my improved commutator-brushes formed, as described, from graphite much better results are attained 45 than can be attained by the use of the ordinary forms of brushes from the fact that by the reason of the lubricating properties of the

graphite composing the brush the wear upon the commutator is greatly lessened, the commutator is kept smooth, and the contact between the commutator and the brush rendered more perfect.

The necessity of cleaning and sandpapering and otherwise polishing or smoothing the surface of the commutator, which is necessary in the use of the ordinary forms of commutator-brushes, is entirely done away with by the employment of my improved form of brush, and the surface of the commutator is kept bright and clean at all times.

Any metal other than copper may obviously be employed to coat the surface of the graphite, if desired, this metallic coating serving to materially strengthen the brush and to prevent the edges being chipped off in use 65 and thereby adding to the durability of the brush.

Having thus described my invention, what I claim as new, and desire to secure by Letters Patent of the United States, is—

1. The herein-described commutator-brush, comprising a suitably-shaped body, composed of a plurality of strips or bars, each independently coated with a film or covering of electrically-deposited metal, and the series of 75 strips or bars united together by means of a second film or covering of metal, substantially as described.

2. The herein-described commutator-brush comprising a suitably-shaped body composed 80 of a plurality of strips or bars of graphite, each covered with a film or coating of electrically-deposited metal, said strips or bars being united together by means of a second coating of metal, substantially as described. 85

In testimony that I claim the foregoing I have hereunto set my hand, at Milwaukee, in the county of Milwaukee and State of Wisconsin, in the presence of two witnesses.

ROBERT HIRSCH.

Witnesses:

H. G. UNDERWOOD,
WM. KLUK.
